UNITED STATES PATENT OFFICE.

JAMES ROSE, OF LANCASTER, PENNSYLVANIA, ASSIGNOR OF ONE-HALF TO DAVID ROSE, OF LANCASTER, PENNSYLVANIA.

LAMP STANDARD AND SHADE HOLDER.

1,157,180.

Specification of Letters Patent. Patented Oct. 19, 1915.

Application filed March 12, 1913. Serial No. 753,731.

To all whom it may concern:

Be it known that I, JAMES ROSE, a citizen of the United States, residing at Lancaster, in the county of Lancaster and State of Pennsylvania, have invented certain new and useful Improvements in Lamp Standards and Shade Holders, of which the following is a specification.

This invention relates to standards and shade holders for lamps, and is particularly intended for use in connection with electric lights.

The object which I have in view is to provide a standard and shade holder of such construction as to permit of the ready folding of the shade holder in order to adapt the same for packing in a small compass for shipment or for storage in a small space.

A further object is to provide an article of the kind described of a construction permitting the ready attachment and detachment of a shade of suitable fabric, in order that the appearance may be changed at will.

With these objects in view the invention consists of the standard and shade holder having the generic and specific features of construction and arrangement of the parts substantially as hereinafter described and claimed.

The invention is illustrated in the accompanying drawing in which:

Figure 1 is a side view of the device in position for use; Fig. 2 is a side view showing the shade lowered; Fig. 3 is a side view showing the shade folded for purpose of shipping or storage; Fig. 4 is a side view of the frame of the device with the cover and a portion of the frame removed, the parts being shown in the position assumed to spread a shade to the fullest extent; and, Fig. 5 is a view of the frame showing the positions assumed by the parts when the frame is closed.

In this drawing 1 represents a standard which may be of any suitable material, being preferably in order to adapt it for the purposes of the invention of hollow metal. Formed with or attached to the lower portion of the standard 1 is a base 2 the size of which is such as to give stability to the structure which rests upon it.

Fixed to the standard near the upper end thereof is a disk or ring 3, and attached to the outer edge of such disk or ring by a hinge or pivot joints 4 are a series of arms 5. Lo-

cated a suitable distance below the disk 3 is a second disk 6 which is provided with an opening permitting its free sliding up and down on the standard 1. The standard is provided with a spring catch 7 movable into and out of the standard, and so located as to bear upon the upper face of the disk 6 when the latter is in an elevated position.

Connected each at one end to the disk 6 and at the other end to the arms 5, are a series of braces 8 which serve to move the arms up and down on their joints as the disk is moved up or down on the standard to bring the arms to an upper or raised position, or to move them to positions substantially parallel to the standard.

The cover 9 of any suitable material, preferably of ornamental fabric is secured to the upper end of the standard 10 which projects above the disk 3, and to the outer ends of the arms 5, by sewing or in any suitable way, which permits of the ready removal of one cover and the substitution of another.

Projecting from the standard at points between the disks 3 are hollow arms 11 the openings in which communicate with the opening in the standard 1. Located on these arms of which there may be any suitable number are the sockets 12 into which are placed the ends of incandescent or other electric bulbs 13.

A suitable electric conductor 14 is connected with the sockets 12 in any suitable way as by passing the same up through the hollow standard and through the arms 11 to the sockets.

The respective diameters of the disks 3 and 6 are such that when the disk 6 is lowered on the standard bringing down the arms 5 and the cover connected therewith to positions substantially parallel with the standard, the arms and parts connected therewith are maintained in positions free from the sockets and lights. Thus the structure may be folded to occupy a space of a diameter corresponding to that of the larger disk 3. This permits the compact folding of the device for shipping, and also permits it being reduced to a small compass, to occupy a small space when not in use.

The diameter of the base is preferably as shown of a diameter greater than that of the disk 3, so that when the shade is folded for shipping or storage the ribs and cover come within the area of the base, affording, par-

105

110

ticularly in shipping protection for the parts.

The described arrangement permits not only of the ready adaptment for shipment or storage, but also permits of the lowering of the frame in order to bring the cover to a position to shade the lights at any desired height, and in this way allowing of the use for reading or other purposes irrespective 10 of the location of the lamp in reference to that of the user.

I claim;

1. An article of the kind described comprising a standard, a disk attached to the standard, arms pivotally attached to the disk, a second disk arranged on the standard and slidable thereon, braces connecting the second disk and the arms, and light fixtures attached to the standard between the disks, 15 the radii of the disks being greater than the distance which the fixtures project from the standard.
2. An article of the kind described comprising a standard, a disk attached to the standard, arms pivotally attached to the disk, a second disk arranged on the standard and slidable thereon, braces connecting the 20

second disk and the arms and light fixtures attached to the standard, the radii of the disks being greater than the distance which 30 the fixtures project from the standard.

3. An article of the kind described comprising a standard, a disk on the standard, light fixtures extending from the standard below the disk, arms pivotally attached to 35 the disk, means movable up and down on the standard and connected to the arms by braces, and a base for the standard, the diameter of the base being greater than that of the disk.

4. An article of the kind described comprising a standard, pivoted arms, means for connecting the arms to the standard, means movable longitudinally of the standard, a connection between such means and the arms, 40 light fixtures extending from the standard, and a base for the standard.

In testimony whereof I affix my signature in presence of two witnesses.

JAMES ROSE.
